UNITED STATES PATENT OFFICE.

JOHN F. KELLY, OF TRENTON, NEW JERSEY, ASSIGNOR TO THOMAS MADDOCK'S SONS COMPANY, OF TRENTON, NEW JERSEY, A CORPORATION OF NEW JERSEY.

DESIGN FOR A LAVATORY.

No. 38,040.

Specification for Design.

Patented May 29, 1906.

Application filed April 26, 1906. Serial No. 313,873. Term of patent 14 years.

To all whom it may concern:

Be it known that I, JOHN F. KELLY, a citizen of the United States, residing at Trenton, in the county of Mercer and State of New Jersey, have invented a new, original, and ornamental Design for Lavatories, of which the following is a specification, reference being had to the accompanying drawings, forming part thereof.

Figure 1 is a top plan view, Fig. 2 is a bot-

tom plan view, and Fig. 3 is a front edge view, of a lavatory embodying the design.

I claim—

The ornamental design for a lavatory, as shown.

JOHN F. KELLY.
